E. G. ALDEN

LOOSE LEAF BINDER

Filed Oct. 16, 1922

UNITED STATES PATENT OFFICE.

EARLE G. ALDEN, OF DENVER, COLORADO, ASSIGNOR TO THE ARCHLOK LOOSELEAF COMPANY, OF DENVER, COLORADO.

LOOSE-LEAF BINDER.

Application filed October 16, 1922. Serial No. 594,900.

To all whom it may concern:

Be it known that I, EARLE G. ALDEN, a citizen of the United States of America, residing at Denver, in the county of Denver and State of Colorado, have invented certain new and useful Improvements in Loose-Leaf Binders, of which the following is a specification.

This invention relates to loose leaf binders of the type arranged for the rapid removal and replacement of large sheets and has for its principal object the provision of a device of this character in which the sheets may be quickly and easily removed and which is capable of expansion to accommodate varying amounts of sheets.

Another object of the invention is to provide a simple and efficient lock whereby the binding loops can be readily locked in either the open or closed positions or any other desired intermediate positions.

A further object of the invention is to provide a device of this character in which the sheets will lie perfectly flat in both the open and closed positions, thereby affording a perfect writing surface and exposing the full length of the sheet to view.

Other objects and advantages reside in the detailed construction of the invention, which result in simplicity, economy and efficiency, and which will become more apparent from the following description.

In the following detailed description of the invention reference is had to the accompanying drawing which forms a part hereof. Like numerals refer to like parts in all views of the drawing and throughout the description.

In the drawing:—

Fig. 1 is a longitudinal vertical section through the invention, taken on the line 1—1, Fig. 2.

Fig. 2 is a plan view of the binding portion of the invention, partially in section, said section being taken on the line 2—2, Fig. 1.

Fig. 3 is a vertical cross section taken on the line 3—3, Fig. 2.

Fig. 4 is an enlarged cross section through the operating mechanism.

Fig. 5 is a side elevation of a portion of

the binder showing the leaves in the open position. This view shows the method of opening the cover.

Fig. 6 is a fragmentary view of the cover, 55 showing the slots employed therein, to allow the cover to be opened over the binder loops.

Fig. 7 is a detail view of the joint between the fixed and rotatable portions of the binding loops. 60

Let the numeral 10 designate the base board of the improved binder, consisting of a solid portion 11, and a hollow portion 12. In the hollow portion is contained the binder-operating mechanism. The binder 65 consists of a series of rotatably mounted vertical standards 13, turned in a semicircle or loop 23 at their upper extremities, and co-acting with a corresponding series of vertical standards 14. In the drawing, three sets 70 of members 13 and 14, are shown, but it is understood that as many sets may be employed as desired, according to the size of sheets used in the binder.

Vertical standards 14 are securely fixed 75 in sockets 15, formed in the hollow portion 12, of the base 10, and terminate in a beveled top, as shown in Fig. 7. The leaves to be used in the binder, designated on the drawing by the numeral 16, are punched 80 with round holes, corresponding in size and spacing to the vertical standards 14, and placed over said standards.

Standards 13 are each rotatably mounted in a bearing 17, formed in the hollow portion 12 of the base 10, and terminate at their upper extremities in beveled ends which are adapted to fit closely against the beveled ends of the standards 14, and form what is practically a continuous rod over which the 90 sheets 16 are turned when the binder is opened.

A cover 18, of stiff binder's board or other material, is used to cover the sheets when the binder is closed. Cover 18 is provided, 95 near its bound extremity, with a hinge 19, and a turned-back portion 20. In the turned-back portion round holes 21 are placed which fit over the standards 13 and prevent the removal of the cover. Coacting 100 with the holes 21 are slots 22, see Fig. 6, of sufficient length to fit over the loop 23 and

enclose both standards 13 and 14. When it is desired to open the cover 18, from the closed position, shown in Fig. 1, to the open position, shown in Fig. 5, the cover is lifted 5 on the standards 13 and 14, to the loop 23 and opened as shown in broken lines in Fig. 5, the slots 22 allowing the loops 23 to pass through the cover; the cover being turned upon the hinge 19.

10 Fixed to each of the standards 13, within the hollow portion 12 of the base, is a lever arm 24 set at an angle of 45° with the plane of the loop 23. A bar 25 passes throughout the length of the hollow base portion 12 and 15 pivotally connects with each of the lever arms 24, as shown at 26, thereby causing all of the standards 13 to rotate in unison when any of them are rotated. One extremity of the bar 25 terminates in an enlarged portion 20 27, in which is formed a series of transverse slots 28.

Horizontally pivoted over the portion 27 of the bar 25 is a rocker arm 29, one extremity of which is turned downward so as to 25 engage in the slots 28; the other extremity of which is pivoted to a vertical shaft 30, which extends above the base, through a bushing 31, and terminates in a push button 32. Rocker arm 29 is held in engagement 30 with the slots 28 by a leaf spring 33 secured to the base portion 12.

A coil spring 34 is secured to one of the levers 24, and connects with a post 35 in the base. Spring 34 serves to hold the 35 beveled ends of the loops 23, in contact with the beveled ends of the standards 14.

When it is desired to remove or insert a sheet in the binder, the leaves are opened to the proper place, as shown in Fig. 5; the 40 button 32 is depressed, which in turn releases the arm 29, from the slots in the bar 25, and the loops 23 are turned to position shown in broken lines at 36, Fig. 2; the button is now released and the arm 29 engages in one of the notches 28, thereby locking all of the loops in the open position; the sheet is now inserted or removed as desired, and the button 32 again depressed which releases the arm 29 from the notches 45 28, and allows the spring 34 to cause the loops to reengage the extremities of the standards 13, and the complete binder is again ready for use. It will be seen that the loops are always locked in position so 50 that the danger of disengaging the leaves by dropping the binder or other mistreatment is eliminated.

The hollow portion 12, of the base 10, is secured to the solid portion 11, by means 55 of rivets 37 or in any other suitable manner so that it may be readily removed for repairs.

It will be noted that the standards 13 are jointed, as shown at 38, Fig. 4, and that the 60 standards 14 are removable. This allows for

the expansion of the binder as more sheets are added, since longer standards can be readily put in place of the short ones, without disturbing the binder mechanism. Short 70 lengths of the standard rod could be furnished with the binder, having a male thread on one extremity and a female thread on the other. These lengths could be placed in the standards as expansion was required without discarding the looped and 75 bevel ended portions originally furnished.

The base 10 could be bound in cloth, leather, or other material to match the cover 18, and form a very attractive article.

While I have described and illustrated 80 herein a specific form of my improvement I wish it understood that the same may be varied, within the scope of the appended claims, without departing from the spirit 85 of the invention.

Having thus described the invention, what is claimed and desired secured by Letters Patent is:—

1. A loose leaf binder comprising a base board; a series of vertical standards fixed 90 in said board and adapted to engage the sheets to be bound; a similar series of loop-shaped standards pivoted in said board and adapted to engage said first-mentioned standards; levers secured to said loop-shaped standards within said board; a bar pivoted to all of said levers, said bar being provided with slots or notches; a spring arranged to hold said standards in engagement, and means engaging with said notches to hold 95 said loop-shaped standards in any desired position.

2. A loose leaf binder comprising a base board; a series of vertical standards fixed 100 in said board and adapted to engage the sheets to be bound; a similar series of loop-shaped standards pivoted in said board and adapted to engage said first-mentioned standards; levers secured to said loop-shaped standards within said board; a bar pivoted 105 to all of said levers, said bar being provided with slots or notches; a spring arranged to hold said standards in engagement; a rocker arm pivoted to engage in said notches and a push-button shaft extending into the interior of said board and engaging said 110 rocker arm.

3. A loose leaf binder comprising a base board; a series of vertical standards fixed 115 in said board and adapted to engage the sheets to be bound; a similar series of loop-shaped standards pivoted in said board and adapted to engage said first-mentioned standards; levers secured to said loop-shaped standards within said board; a bar pivoted to all of said levers, said bar being provided with slots or notches; a spring arranged to hold 120 said standards in engagement; a rocker arm pivoted to engage in said notches; a push-button shaft extending 125 into the interior of said board and engaging said rocker arm.

- into the interior of said board and engaging said rocker arm and a spring adapted to hold said rocker arm in engagement with said notches.
5. 4. A loose leaf binder comprising a base board; a series of vertical standards fixed in said board and adapted to engage the sheets

to be bound and a similar series of loop-shaped standards pivoted in said board and adapted to engage said first-mentioned standards, said standards being jointed to allow the addition of sections. 10

In testimony whereof I affix my signature.

EARLE G. ALDEN.
